UNITED STATES PATENT OFFICE.

EDWARD THIRY, OF PASADENA, CALIFORNIA.

FLUSHING DEVICE FOR CLOSETS.

1,160,093.

Specification of Letters Patent.

Patented Nov. 9, 1915.

Application filed March 2, 1915. Serial No. 11,426.

To all whom it may concern:

Be it known that I, EDWARD THIRY, a citizen of the United States, residing at Pasadena, in the county of Los Angeles and State of California, have invented new and useful Improvements in Flushing Devices for Closets, of which the following is a specification.

This invention relates to improvements in flushing devices for toilet tanks and particularly to flushing devices for "lowdown" tanks that are used in connection with closet bowls and the principal object of the invention is to produce a flushing device which may be placed in a lower portion and be operated without the use of rubber valves, seats or mercury seals.

It is also an object to provide a flushing mechanism with a minimum number of movable parts.

It is also an object to provide a flushing mechanism in which air is used as the seal or valve to prevent operation or flushing of the connected bowl.

It is a still further object to have the water in the tank balance the air entrapped to form the seal so that a minimum amount of effort is required to initiate the flushing operations with corresponding diminution of the noise incident thereto.

It is a still further object to provide a flushing mechanism with means to quickly start the siphon into the discharge pipe, thus diminishing the noise of operation.

In the accompanying drawing, forming a part of this specification: Figure 1 is a vertical sectional view taken through a flush tank constructed in accordance with the present invention and through a closet bowl connected therewith, the bowl being turned through an angle to more clearly show the flush tank and its connection to the bowl. Fig. 2 is a similar section, the bowl being also turned at an angle and showing the unsealed position. Fig. 3 is a section of the bells and head of the discharge pipe on a larger scale to more clearly show the contracting of the bells when the tank is full of water ready for flushing. Fig. 4 is a plan view of the discharge pipe with the apron partly broken away.

Heretofore in the operation, especially of "low down" toilets, rubber valves or seats have been used which soon harden and permit leakage, and this type of valve is readily displaced and fails to operate, and where

mercury seals are used to overcome these defects, the expense of maintainance is materially increased. My invention overcomes these defects, uses air as a seal, and accomplishes the result with members impossible to displace under ordinary conditions and with no expense for maintenance together with a decrease in the objectionable noise when in flushing operation.

The details and features of the invention will now be more particularly described, reference being had to the said drawing in which 5 indicates a flushing tank adapted to be mounted upon a wall or otherwise suitably supported a slight distance above the bowl 6 of a toilet closet. The flush may be of any ordinary construction and a flush or discharge pipe 7 extends downwardly therefrom so as to act with the trap 8 preferably built in the closet bowl. The parts are usually arranged so that the pipe 7 is in vertical position and extends into the long leg of the water trap 8. The upper end of the pipe 7 projects upward about half way into the tank 5, and its upper end is formed with a flaring portion 9 having projections 10 upon its upper edge at three or more points.

To aid in the discharge of the water and prevent noise the flaring portion 9 is also provided with a downwardly inclined apron 11, the water leaving the lower edge 12 of this apron, is distributed over the cross section of the discharge pipe 7, forming a plug 90 of water which in falling creates a vacuum and starts the siphon. In the ordinary construction of discharge pipes, the water initially runs down the inside of the pipe 7 leaving an air filled center and making much noise. A bell 14 rests at all times upon the upper ends of said projections 10 as clearly shown in the drawings, and the said bell 14 is made of considerable depth or about equal to the height of the discharge pipes, and its lower edge projects downwardly within a short distance of the bottom of the tank 5. Near the lower edge of this bell 14 perforations 15 are preferably provided to facilitate the action of the water in breaking the siphon quietly when the tank is emptied to the level of these openings.

Secured to the center of the domed portion of the bell and projecting downwardly therefrom is an air tube 16 opening above the bell, the latter being provided with a

central opening to receive said tube while the lower end of the tube extends downwardly into the flush pipe 7 below the bottom of flush tank 5 and to a point preferably about opposite and above the overflow point for the water in the trap 8.

Coöoperating with the bell 14 is an upper bell 17 which is of such shape that its central portion will rest upon the lower bell 14 and close the upper open end of the tube 16, and leaving an annular air space 18 between the bells.

The bell 14 is provided with an eye 19 having an extension 21 loosely fitting into the tube 16 and serving as a guide, but having sufficient clearance so that air may pass out of the pipe 16 when the bell 17 is raised. Bell 17 is provided with an eye 19 by which it is connected to the link 20 forming a member of a link mechanism leading to a convenient operating lever or button.

The tank 5 may be provided with any suitable valve 28 for controlling the supply of water to the tank, the said valve being automatically operated by a float 29 and a float lever 30; the valve 28 being connected with the service pipe 31 in the usual way. An after fill 32 may also be provided extending from the valve 28 and being bent so as to enter the lower bell 14 and pass upwardly therein, its inner end being turned downwardly within the pipe 7 for a short distance. This pipe will supply added water which may be needed to insure the maintaining of the water in the bowl at a proper height, in the usual and well known manner.

In the operation of the device the water will, after a flushing operation, gradually rise in the tank 5 until a proper height has been attained in the tank to shut the valve 28. The bells being contracted, the water will also rise in the lower portions of the bells until the air entrapped within the pipe 7 and between the bells 14, and the water in the trap 8 is slightly compressed, and balances the water in the tank 5, the parts are so proportioned that the water will not rise far enough in the lower bells to overflow into the tube 7.

When it is desired to flush the closet the lever is operated to lift the bell 17, this will release the pressure by allowing the air in the pipe 7 to escape up through the water in the tank by way of the tube 16 and upsets the balance between the said air and the water in the tank 5 and the water will rise in the bell 14 and enter the flush pipe 7 over the upper edge thereof, the apron 11 distributing the water to completely fill the pipe and carry the water out with a minimum amount of noise; a slight pressure of about one quarter of a pound above the ordinary atmospheric pressure being maintained in the air seal. The siphonizing action will be continued until the water has

fallen below the bell 14 to the lever of the holes 15 therein when the siphonizing action will be gradually and quietly stopped. As the level of the water lowers the float 29 moves turning the lever 30 and opening valve 28 to admit water from the service pipe. As the water gradually fills the flushing tank again, the water and air will assume the same relative positions as before the flushing operation. The weight of the bell guided by the rod 30 extending into the pipe 16 immediately returns it to the normal position closing the pipe 16 as the siphoning is established.

While the tank is filling water flows through the refill pipe 32 supplying an amount equal to that lost by the inertia of the water flowing out of the bowl during the flushing operation.

When the water leaves its normal high level the float 29 attains a position such that it closes valve 28 when the tank is ready for another flushing operation.

What I claim is:

1. A flushing mechanism, comprising in combination with a flush tank and a bowl having a water trap therein, of a discharge tube extending from a point midway in said tank through the bottom thereof into the long leg of said water trap, a bell having an opening in the dome thereof, a pipe secured in the opening of said bell and extending downwardly within said flush pipe, means to support said bell in concentric relation and with its dome a slight distance above the open end of said discharge pipe, and a domed closure normally resting on the dome of said bell to close said opening and the open end of said pipe secured therein.

2. A flushing mechanism, comprising in combination with a flush tank and bowl having a water trap therein, of a discharge tube extending from a point midway in said tank through the bottom thereof into the long leg of said water trap, a bell having an opening in the dome thereof, a pipe secured in the opening of said dome and extending downwardly within said flush pipe means to support said bell in concentric relation and with its dome a slight distance above the open end of said discharge pipe, and a domed closure having a guide rod projecting into said pipe, said domed closure being adapted to normally rest on said dome of said bell to close said opening and the open end of said pipe secured therein.

3. A flushing mechanism comprising in combination with a flush tank and a bowl, a water trap in said bowl, a bell having an opening in the dome thereof, a pipe secured in the opening of said dome and extending downwardly within said flush pipe, means to support said bell in concentric relation and with its dome a slight distance above the open end of said discharge pipe, and a

domed closure adapted to normally rest on said apex of said bell to close said opening and the open end of said pipe secured therein.

4. A flushing mechanism, comprising in combination with a flush tank and a bowl having a water trap therein, of a discharge tube having the open end in said tank flare, the other end leading to the said trap, a bell secured to the flaring end of said discharge tube, an air relief pipe extending into said discharge pipe secured at one end in an opening through the discharge of the dome, and a dome closure loosely mounted on the dome of said bell to close the open end of said air relief pipe.

5. A flushing mechanism comprising in combination with a flush tank and a bowl having a water trap therein, of a discharge

tube having the open end in said tank flare, the other end leading to the said trap and with a flared apron secured therein, a bell secured to the flared end of said discharge pipe, an air relief pipe extending into said discharge pipe and secured at one end in an opening through the discharge of the dome, and a domed closure loosely mounted on the dome of said bell to close the open end of said air relief pipe.

In witness that I claim the foregoing I have hereunto subscribed my name this 30th day of January, 1915.

EDWARD THIRY.
